UNITED STATES PATENT OFFICE.

FREDERICK VESPASIAN YOUNG, OF LYNDHURST, NEW JERSEY, ASSIGNOR TO WESTERN ELECTRIC COMPANY, OF NEW YORK, N. Y., A CORPORATION OF ILLINOIS.

TELEPHONE SYSTEM.

1,128,930.

Specification of Letters Patent.

Patented Feb. 16, 1915.

Application filed June 19, 1914. Serial No. 846,082.

To all whom it may concern:

Be it known that I, FREDERICK V. YOUNG, a citizen of the United States, residing at Lyndhurst, in the county of Essex and State 5 of New Jersey, have invented certain new and useful Improvements in Telephone Systems, of which the following is a full, clear, concise, and exact description.

This invention relates to telephone systems, and more particularly to such systems of the central energy type in which there may be one or more stations connected to a single line.

The object of this invention is the production of improved signal-controlling means for such systems.

In accordance with this invention there is provided an electromagnetic means for automatically removing the ringing current 20 from the line, and connecting an operator's telephone set therewith when a called party removes the receiver from the switch hook. Said electromagnetic means may comprise a relay having a plurality of windings, one 25 of which is normally short-circuited through a contact of a second relay. The removal of a receiver from a switch hook operates said second relay, which removes the short, permits the first mentioned relay to operate, 30 disconnecting the ringing current, and connecting the operator's telephone set to the line.

The accompanying drawing illustrates diagrammatically one of the arrangements 35 by which this invention may be effectuated.

In the drawing there is shown a telephone line terminating in a switchboard located at a central office. The switchboard is provided with an ordinary standard operator's 40 set A, which is normally connected, through the contact of an operating key B, to a telephone line. This connection may be traced by the following path: starting from contact 40 of the operating key B, line wire 45 1, through the various substations C, D and E, back over line wire 2, contact 38, conductors 16, 4, through the operator's set A, conductors 3, 18, back to contact 40. The manner of signaling central is the same as is 50 customarily employed in signaling central in the ordinary common battery system. In event a party wishes to call central from one of the substations C, upon removing the receiver from the switch hook the line 55 relay 8 is energized. The energization of

line relay 8 closes contact 13, which completes a circuit through the line lamp 14, causing said lamp to be lighted.

When the central operator wishes to ring one of the substations, ringing current is 60 applied to the line by actuating the operating key B. The actuation of the key B closes contacts 37, 39 and 41. The closing of contact 39 causes the energization of relay 7 by completing the following circuit: 65 battery 10, conductor 20, contact 39, conductor 17, through one of the windings of relay 5, conductor 25, contact 33, conductors 27, 21, through the coil of relay 7, back to battery. It may be stated here that relay 70 5 is comprised of two windings, one of which is normally short-circuited. The current which flows through the other winding is not sufficient to energize the relay 5, but is sufficient to cause said relay to be saturated 75 so that it is rendered sensitive to a small amount of additional current. Therefore, whenever the short is removed from the winding normally short-circuited, the relay 5 immediately pulls up.

The energization of relay 7 over the path just described closes contact 36. This causes ringing current to be sent over the line wires 1 and 2 by closing the following circuit: 80 from battery 11, through the generator 12, 85 conductor 23, back contact 32 of relay 5, conductor 15, contact 37, line wire 2, through coil of relay 9, line wire 1, contact 41, conductor 19, back contact 35 of relay 5, conductor 26, coil of relay 6, conductor 22, contact 36, back to battery 11. Relay 9 is of 90 a type which is responsive to alternating current, while relay 6 is only energized by direct current. Consequently, relay 9 will be energized by the ringing current sent 95 over the line, closing contact 45. The closure of contact 45 completes a circuit through the lamp 46, causing it to be lighted. The ringing current flowing from the generator 12 will operate the signal 42. We thus 100 have two means for attracting the attention of the individuals at the various substations.

Since relay 6, as mentioned above, is only responsive to direct current, it will not be energized at the time ringing current is applied to the line wires 1 and 2 over the circuit just described. However, when the receiver is removed from the switch hook at 105 substation C, a circuit is completed which permits the flow of direct current, and re- 110

sults in the energization of relay 6. The actuation of relay 6 removes the short from the winding of relay 5 that is normally short-circuited by opening contact 33. The 5 two windings of relay 5 are now cut in series, and current sufficient to energize said relay flows through the following path: battery 10, conductor 20, contact 39, conductor 17, both windings of relay 5, conductors 28, 21, the coil of relay 7, back to battery. The energization of relay 5 removes the ringing current by opening contacts 32 and 35, while the closing of contacts 10 31 and 34 connects the operator's set A to the line wires 1 and 2 by establishing the 15 following circuit: starting from contact 41 of the operating key B, line wire 1, through the substation C, line wire 2, contact 37, conductor 15, front contact 31 of relay 5, conductors 29, 4, through the operator's set A, conductors 3, 30, front contact 34 of relay 5, conductor 19, back to contact 41. The opening of contact 35 at the time the relay 20 5 is energized, breaks the circuit through relay 6, causing its deenergization and the 25 consequent closing of contact 33, which in turn short-circuits the normally short-circuited winding of relay 5. By restoring the operating key B to normal position, current 30 may be removed from relays 5, 6 and 7, and at the same time a circuit for conversational 35 purposes will still be maintained between the substation C and the operator's set A, since, as described above, the operator's telephone set is normally connected to the telephone line.

From the above description it will be seen that the application of ringing current to a 40 subscriber's line is automatically controlled by an electromagnetic device which responds immediately when a called subscriber removes the receiver from the switch hook.

What is claimed is:

1. A telephone system comprising a central office, a telephone line terminating thereat, an operator's telephone set normally connected to said line, a source of ringing current, switching means for disconnecting said operator's telephone set from said line 45 and connecting thereto said source of ringing current, and electromagnetic means operated upon response of the called party to disconnect said source of ringing current from said line and connect therewith said 50 operator's telephone set.

2. A telephone system comprising a central office, a telephone line terminating thereat, an operator's telephone set normally connected to said line, a source of ringing current, switching means for disconnecting 60 said operator's telephone set from said line and connecting thereto said source of ringing current, and an electromagnetic device for automatically disconnecting said ringing current from said line and connecting said operator's telephone set therewith, said electromagnetic device having a plurality of windings, one of which is normally short-circuited. 65

3. A telephone system comprising a central office, a telephone line terminating thereat, an operator's telephone set normally connected to said line, a source of ringing current, switching means for disconnecting 70 said operator's telephone set from said line and connecting thereto said source of ringing current, an electromagnetic device having a plurality of windings, one of which is normally short-circuited, and means actuated upon the removal of a receiver from a 75 switch hook for removing the short from said normally short-circuited winding, whereby said electromagnetic device is actuated to disconnect said ringing current from said line and connect said operator's telephone set therewith. 80

4. A telephone system comprising a central office, a telephone line terminating thereat, an operator's telephone set, sources of ringing current and direct current at said 90 central office, a relay at said central office having a plurality of windings, switching means for completing a local circuit including a winding of said relay and said source of direct current and for connecting said 95 source of ringing current to said line, and means at said central office actuated upon removal of a receiver from a switch hook to include another winding of said relay in 100 said local circuit, whereby said relay is operated to disconnect said source of ringing current from said line and connect said operator's telephone set therewith. 105

In witness whereof, I hereunto subscribe my name this 17th day of June A. D., 1914.

FREDERICK VESPASIAN YOUNG.
